UNITED STATES PATENT OFFICE.

CHARLES N. DEVERALL, OF BUFFALO, NEW YORK, ASSIGNOR TO RUDOLPH WURLITZER MANUFACTURING COMPANY, OF NORTH TONAWANDA, NEW YORK, A CORPORATION OF NEW YORK.

CONTACT BLOCK FOR ELECTRIC ORGANS AND THE LIKE.

Application filed May 17, 1922. Serial No. 591,622.

This invention relates to a contact block or make and break device which is more particularly designed for use in connection with electrically controlled musical instruments, such as orchestral and other organs, this block being provided with flexible contact members adapted to be bridged and deflected by a switch member carried by an organ key, to complete an electro-pneumatic circuit for operating the action and other parts of the instrument.

The flexible arms or branches of each of the contact members or wires are usually L-shaped, and when they are flexed at the bend or junction of the arms they gradually weaken and ultimately break at that point.

It is one object of this invention to improve the construction of such contact blocks with a view of overcoming the above objection and prolonging the life of the contact wires.

A further object is to tightly secure the wires in the blocks by simple and inexpensive means.

In the accompanying drawings: Figure 1 is a side elevation of the contact block, showing diagrammatically its application to the associated parts of an organ. Figure 2 is a bottom plan view thereof. Figure 3 is a vertical longitudinal section of the block. Figure 4 is a transverse section on line 4—4, Fig. 3. Figure 5 is a perspective view of the main block section. Figure 6 is a similar view of the heel section.

Similar characters of reference indicate corresponding parts throughout the several views.

10 represents a main or front section forming the body portion of the contact block and provided in its underside with a series of vertical saw cuts or guides 11 extending lengthwise thereof. Said section is provided with an overhanging rearward extension 12 forming a rearwardly-facing transverse shoulder 13. Arranged in these saw cuts are the flexible contact members each of which is preferably constructed of a single length of spring wire bent into substantially L-shape and forming a long horizontal arm 14 and a short upright arm 15. The flexible horizontal arm of each contact wire is free to vibrate in one of the saw cuts of the block with its free end projecting beyond the front end of the latter, while

the vertical arm is confined in an opening 16 in the extension of said front section 10 and projects a suitable distance above the same, as shown in Figs. 3 and 5. The several openings 16 are disposed in the rear of the shoulder 13 of the front section of the block, so that the horizontal arms 14 extend forwardly beyond said shoulder.

Glued or otherwise secured to the underside of the extension 12 to overlie and cover the bend 17 and the adjacent rear portions of the contact wires, is a heel block or rear section 18 whose front end abuts against the shoulder 13 of the front section 10, as shown in Figs. 1 and 3.

By this arrangement, when the contact wires are depressed by an actuating part, such as the usual switch member 19 on the underside of an organ key 20, flexing of the wires takes place at a point in front of and remote from the bends 17, the upper front edge of the heel section of the block serving as the fulcrum about which said arms are flexed. By thus transferring the fulcrum or flexing portions of the horizontal contact arms from their bends or angles to a point at a distance therefrom, the bent portions of the wire are allowed to remain at rest and the vibrating and flexing action of the horizontal arms is confined to their straight portions, thereby avoiding weakening and breakage of the wires at the bends and greatly increasing the durability of the contact-block.

In gluing the separate heel section to the main section of the block, the customary gluing clamps press the upper face of the heel section tightly against the rear portions of the contact arms 14 and the contiguous extension 12, holding the wires firmly in place and insuring flexion thereof at a point in advance of their bends 17.

To illustrate its application, the contact block is herein shown in connection with an organ key for controlling the electro-magnets 21, which in turn control the customary action of the organ pipes. 22 indicates the circuit containing the series of electro-magnets which correspond in number to the pipes 23, one wire of each magnet being connected to a corresponding vertical arm 15 of the contact block, while the other wire of each magnet is connected to a current supply wire 24 leading from one

of the terminals of a battery 25 or other source of current. The wire 26 leading from the other battery terminal is connected by branches 27 to the vertical arms of the 5 remaining contact wires of the block, there being one more contact wire than there are magnets for a given set. In the normal position of the parts, the magnet-circuits are open. When it is desired to bring certain pipes of the instrument into action, the corresponding control stop or tablet of the instrument (not shown) is actuated, so that when the operator depresses one or another of the organ keys, its switch contact 19 10 bridges the wires of the corresponding contact block, closing the magnet-circuits and operating the customary action to sound the corresponding pipes.

The block, including its glued sections 20 and the contact wires clamped between them, constitutes a unitary article of manufacture, separate from the customary rail 28 upon which they are mounted and secured. This construction insures a tight and firm attachment of all the wires to the block and their flexion at a point away from their bend, unlike the structures hitherto in use, in which the wires are laid loosely in the saw cuts of a solid non-sectional block which 25 is then applied to the rail.

I claim as my invention:

1. As an article of manufacture, a sectional contact-block, comprising a front section, a rear section secured to the underside 30 of said front section, and a contact mem-

ber secured at its rear end to said front section and capable of vertical flexion and vibration thereon, said rear section extending forwardly beyond the rear end of said contact-member, and the portion of the latter adjacent to its rear end resting upon 40 said rear section.

2. As an article of manufacture, a sectional contact-block, comprising a front section provided with a reduced overhanging rearward extension, a rear section secured to the underside of said reduced extension, and a flexible L-shaped contact-member having its upright arm secured in said extension, the horizontal arm of said contact-member being capable of vertical flexion and vibration, said rear section extending forwardly beyond said upright arm, and the adjacent portion of said horizontal arm resting upon the rear section, said block with 55 its contact member being a unitary structure separate from the customary rail upon which the same is adapted to be mounted.

3. As an article of manufacture, a sectional contact-block, comprising a front section provided with a reduced overhanging rearward extension, a rear section secured to the underside of said reduced extension and having its bottom substantially flush with that of the front section, and a flexible 60 contact-member secured at one end to said front section and fulcrumed upon the rear section at a point beyond the attachment of said member to the front section.

CHARLES N. DEVERALL.
